ABSTRACT OF THE DISCLOSURE

The invention relates to an ocean floor sediment cover in which a linear tube, open at one end and provided with a transverse fracturable wall, includes an explosive charge actuated by a magnetic switch. The charge breaks the wall and allows water to enter the tube to drive it into the sea bed by implosion.

The object of this invention is to provide a mechanical device which by use of the external hydrostatic pressure permits a tube to be accelerated at sufficient marine depth. This accelerated tube, if fitted with a penetration nose, may be used as a sediment corer.

The device is lowered down to the sea floor by means of a cable and the tube is recovered; the low cost cast-iron piston is eventually lost.

An embodiment of device in accordance with the invention is hereinafter particularly described with reference to the accompanying drawings, wherein:

FIG. 1 is a diagrammatic side elevation of the tube and piston.

FIG. 2 is a side elevation of a practical embodiment.

FIG. 3 is a partial longitudinal section of a detail of an igniter for the tube.

FIG. 4 is a partial cross section of a detail.

The device is light in weight and is essentially composed of a light metallic tube, a heavy piston, and a light cap.

A tube 1 is closed at one end by a cap 2, and at the other by a piston 3 thereby retaining in the reservoir 4 a certain volume of partial vacuum or of air at atmospheric pressure.

The assembly of tube, cap and piston is submitted to the external forces created by the hydrostatic pressure statically counterbalanced by the internal forces of the rigid mechanical assembly, until a release device 5 frees the piston with respect to the tube. Then the tube 1 is accelerated downward due to the vertical force applied to the cap 2, and the piston 3, due to the pressure force applied to it, is accelerated upward. If the mass of the piston is M and m the mass of the tube and the cap, and if friction is neglected, one can write $Mv = mV$ when v is the instantaneous speed of the piston during the propulsion period and V is the instantaneous speed of the tube and the cap.

During the propulsion period the piston 3 compresses the air stored in the tube 1 until the pressure reaches the external ambient pressure. The vertical internal forces are then equal to the vertical external forces and the kinetic energy of the piston is sufficient to drive away the light cap 2 of the tube. Then only the tube has a large downward final velocity while cap and piston travel upward at a lower speed.

The system can be reversed to accelerate downward a light piston. Then the tube has to be heavy, the cap remaining light.

If the tube is long enough the speed limit can be reached without the use of a heavy piston and a simple diaphragm is sufficient.

The following is a description, given by way of example, of a device used as a sediment corer, see FIG. 2.

The corer is made of three lengths, 6, 7, 8 of light alloy

2

tube of internal diameter 127 mm. and external diameter 147 mm.

The tubes 7 and 8 are each six metres long and are connected by a long watertight joint 9. The lower end of the tube 7 is closed by a glass diaphragm 10 able to sustain great marine pressure.

The upper end of tube 8 is closed by a watertight cap 11. Tubes 7 and 8 are used as reservoirs of energy, and air at atmospheric pressure is stored in them. Tube 6 is connected to the end of tube 7 by an overlapped joint in which a cast iron piston 12 sides loosely (with a clearance of the order of $\frac{3}{10}$ mm. on the diameter).

At the lower end of tube 6 a nylon core catcher actuated by pressure is installed. Tube 6 is six metres long or less. The piston 12 is prevented from falling by means of a small shear pin which holds it in tube 6.

A tube 13 has directional fins. It is two metres high and has an inside diameter of 250 mm.

The corer is suspended by means of two wires 14, terminated by retaining rings. The rings are held in a release mechanism 15. The system is balanced by a counterweight 16 suspended on a wire 17.

The wire 17 is approximately thirty metres in length. A retrieving wire 18 is also thirty metres in length. A small wire 19 (diameter 2 mm.) connects the release mechanism 15 to an implosion igniter 20.

When mass 16 reaches the sea floor, the corer is freed by the release mechanism 15, wire 19 is put under tension and cover 21 is withdrawn. Then the glass diaphragm 10 is broken. The implosion process is then started.

Piston 12 starts moving upward and the tube assembly starts moving downward at about the same speed if weight of tube assembly is equal to the weight of the piston, i.e. each is 150 kg. When air inside the tube is compressed at ambient pressure the piston pushes cap 11 away. The piston and the cap follow their course upward and are lost. Although, in the present system the piston is lost a simple mechanical system can be devised to recover it. A slight slope on top of the piston deviates the course of the piston when it enters the water and this way any collision between piston and release mechanism is avoided. The tube assembly then penetrates the sediments at high speed and the high kinetic energy gives a great penetration with a light equipment.

Supposing the system to be imploding at a depth of 2,500 m. and the piston weighing half the total weight of the tube assembly, the energy available to accelerate the tube is about 1200K joules.

If the tube 6 is made long enough (about six metres) no piston is needed due to the fact that the stored energy is quite large, and the water channelled in tube 1 acts as a piston at the beginning of the implosion. The total efficiency of the system is however slightly smaller.

The tube assembly is retrieved from sediments by the cable 18. The following describes the principle of the igniter, see FIG. 3.

The cover 21 attached to the release cable 19 is made of soft iron. When in place it surrounds a magnet 22 and this way closes the magnetic field existing. 23 is a magnetic switch which closes if submitted to an external magnetic field. This switch 23 is mounted in with a 12 v. battery 24 and an explosive charge 25. The charge is glued on glass diaphragm 10.

When the corer 7 is retrieved the magnetic field of magnet 22 passes through the non-magnetic coring tube and switch 23 is closed. The charge then explodes and the shockwave breaks glass diaphragm 10. The water can then flow freely upward in tubes 7 and 8.

The shapes, dimensions, arrangement and material of the various parts of the system can be changed without

altering the general concept of the invention herewith described.

I claim:

1. A hydrodynamic accelerator comprising a linear tube open at both ends, a fracturable transverse wall disposed across the tube inward of a first end of the tube, an explosive charge adjacent to said transverse wall, an electrical circuit including a current source and a magnetically-operable switch disposed in the tube and connected to the explosive charge, a magnet positioned externally on the tube adjacent to the switch, a magnetic keeper removably positioned adjacent the magnet, means for removing the keeper from the magnet, and a closure for the second of the tube.

2. A hydrodynamic accelerator, as claimed in claim 1, in combination with a relatively massive piston positioned with clearance in the tube externally of the fracturable transverse wall.

3. In combination, for use as a deep-sea sediment coring device, a hydrodynamic accelerator as claimed in claim 1, a tubular supporting head removably engaged on the second end of the tube, a suspension means including a cable, a latching device by which the supporting head

is separably connected to the suspension means, a probe depending from the latching device for release of the latching device when the probe contacts and becomes supported by the sea bed, and a flexible connector coupling the suspension means for fracturing the transverse wall for operating said fracturing means when the supporting head has become separated from the suspension means.
